UNITED STATES PATENT OFFICE.

HENRY P. CLAUSEN, OF MOUNT VERNON, AND CHARLES L. GOODRUM, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE SYSTEM.

1,407,985.

Specification of Letters Patent. Patented Feb. 28, 1922.

Application filed July 14, 1917. Serial No. 180,609.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Telephone Systems, of which the following is a full, clear, concise, and exact description.

This invention relates to telephone systems, and more particularly to subscriber-controlled machine switching systems, the object, in this instance, being to provide a type of selective switch in which a double selection may be made through one setting of calling device.

A feature of the present invention is a means responsive to the manner of setting a calling device, whereby a selection is made which is independent of that made in response to the position in which the calling device is set. According to this feature, a dial switch is provided which may be rotated in either a clockwise or a counter-clockwise direction, which, when and while being rotated in one direction, will cause an impulse to be transmitted to accomplish an additional selection in a seized selector switch.

In most well-known types of selective switches, current is supplied to the line, which has seized the switch, through a so-called line relay which then becomes responsive to the rapid opening and closing of the line circuit through a calling device at the substation. In addition, there is provided in the present instance a differentially wound relay through the windings of which this line current is caused to travel. Being differentially wound, this relay is unresponsive to such current. However, if the balance of the line is disturbed, it becomes responsive. The dial switch is therefore so arranged that while being set through rotation in one direction, the balance of the line will be temporarily disturbed, upon which the before-mentioned relay responds, locks itself in its actuated position and causes thereby an additional selection in the selective switch.

It is thought the invention may best be understood by reference to the accompanying drawing, in which a calling substation, a line

finder switch, a connector switch, and two 55 called substations have been diagrammatically represented.

An idea of the general construction of a dial switch adapted to rotate in either direction may be had from the patent to H. P. 60 Clausen, No. 1,337,198, issued April 20, 1920.

The dial switch used in the present arrangement is shown in association with the subscriber's station S¹. It consists essentially of the dial D, a set of impulse springs 65 C, a finger stop S, and an associated contact 1, which is operated only during the setting of the dial and while the dial is being rotated in a clockwise direction.

When the subscriber at S¹ removes his receiver from its hook, the line finder switch LF is actuated to extend the line to the selector switch SS in a manner well-known to one skilled in the art. A circuit is thereupon established from ground, the right-hand 70 winding of line relay LR, the right-hand winding of relay 2, the first position contact and side-switch wiper W¹, to and through the apparatus of the subscriber's substation S¹, the side switch wiper W² and its first position contact, the middle winding of relay 2, the left-hand winding of relay LR, battery and ground. The right-hand and middle windings of relay 2 are arranged so that the current flowing over them in the circuit just 75 described and in the manner described is not effective in energizing the relay. Relay LR on the other hand is energized in this circuit, and in attracting its armature energizes the release magnet R over a circuit extending from ground, the armature and alternate contact of relay LR, the winding of relay R, battery and ground.

It should be noted that the release relay in this system is adapted to be energized 80 throughout the period during which the selector switch SS is in operation, in somewhat the same manner as is disclosed in the patent to F. A. Lundquist, No. 1,252,463, issued January 8, 1918.

The release relay R attracts its armature and extends a ground from its armature and contact, back into the circuit of the line finder switch to hold this switch actuated until the conversation is terminated.

Upon the manipulation of the dial D (assume it to be manipulated in a counter-clockwise direction), the armature of the line re-

100

105

lay is caused to vibrate. Upon the first retraction a circuit is established from ground, armature and normal contact of relay LR, lower armature and contact of release relay 5 R, the winding of the primary magnet PM, first position contact and side-switch wiper W³, winding of escape magnet E, to battery and ground. The escape magnet E and primary magnet PM are energized in this circuit, the first remaining energized until the termination of the series of impulses, due to its slow releasing characteristic, and the second causing its armature to vibrate in unison with the armature of the line relay. During 10 this series of impulses, the shaft 4 of the selector switch is caused to rotate step by step, bringing first its two sets of brushes b¹ and b² into association with the terminal banks t¹ and t², and second, its two sets of brushes b³ and b⁴ into association with the banks t³ and t⁴ respectively, in the well-known manner. It will be assumed that two impulses have been sent out in the present instance. Therefore, the sets of brushes b³ and b⁴ 15 will be positioned before the terminal banks t³ and t⁴.

Upon the termination of this series of impulses, the escape magnet E retracts its armature, and in so doing steps the side-switch wipers W¹ to W⁴, inclusive, into their second positions, whereupon a circuit is established from ground, the contact and armature of escape magnet E, the secondary off-normal contact SON, side-switch wiper W⁴ 20 and its second position contact, the winding of relay 3, to battery and ground. Relay 3 is energized in this circuit and attracts its armature, establishing thereby a circuit from ground, the armature and contact of relay 3, lower armature and contact of release relay R, the winding of secondary magnet SM, its armature and contact, second position contact and the side-switch wiper W³, winding of escape magnet E, to battery and ground. Upon the first vertical step of the shaft 4 under the influence of the magnet SM, the secondary off-normal contact SON 25 is opened, but circuit for the relay 3 is maintained over the test brush of the set b⁴ from the grounded test terminals of those lines which are at this time busy, through the normal contact and inner right-hand armature of relay 2, the wiper W⁴ and its second position contact, the winding of relay 3 to battery and ground. When the test brush of the set b⁴ encounters a terminal in the bank t⁴ associated with an idle line, the relay 3 will become deenergized and as a consequence will open the circuit for the energization of 30 magnet SM and escape magnet E, whereupon the escape magnet moves the side-switch wipers W¹ to W⁴ inclusive into their third positions.

In the third position of the side switch, 35 line relay LR is disconnected from the line,

and, becoming deenergized, retracts its armature. A circuit is thereupon established from ground in the seized connector switch CS¹ (this ground being established in a manner similar to that described in connection with release relay R) test conductor of the seized trunk, through the test wiper of the set of brushes b⁴, the normal contact and inner-right-hand armature of the relay 2, the side-switch wiper W⁴ and its third position contact, winding of release relay R, battery to ground, whereby the release relay R is maintained energized until the ground is removed from the test conductor of the connector switch at the completion of the conversation.

In the third position the escape magnet is energized over a circuit extending from ground, armature and normal contact of relay LR, third position contact and side-switch wiper W³, winding of escape magnet E, battery and ground, whereby the ground at the contact of this relay is removed from connection with the side-switch wiper W⁴ to prevent the energization of the release relay R when in the restoration of the switch the secondary off-normal contact SON becomes closed.

The connection is further extended through the manipulation of the dial D, 95 through the connector switch CS¹ to substation S².

Assume now that the first manipulation of the dial switch D had been in a clockwise direction, then as the subscriber's finger 100 encountered the member 1 during the setting of the switch, a ground connection will be temporarily made to the line, whereby the balance of the currents flowing through the right hand winding and the middle winding 105 of relay 2 will be disturbed. Specifically, the current through the right-hand winding of the relay 2 will be reduced to zero, since both sides of the winding are now connected to ground, and the current through the 110 middle winding will be increased, since the right-hand winding of the relay 2 and the right-hand winding of the relay LR are shunted out by the ground connection to the member 1. Relay 2 thereupon attracts 115 its armatures and a locking circuit is established from ground, left-hand winding of relay 2, the left-hand armature and contact thereof, the contact member 5, to battery and ground.

Assuming that in its return from set position the dial D causes the actuation of the contact C twice, then the brush shaft 4 as before will be rotated two steps, and the brush set b³ will be positioned in association with the terminal bank t³. The operation of the various relays within the selective switch in this case is the same as that just described, the only difference being that the conversational circuit through the three 130

right-hand armatures of the relay 2 is now transferred from brush set b^4 to brush set b^5 . At the end of the secondary movement of the selector switch, a trunk leading to the connector switch CS² will be seized and the connection further extended to substation S³.

Upon the termination of the conversation the shaft 4 in its return to normal through 10 the projection 6 strikes a lever 7, which in turn momentarily actuates contact member 5, whereby the locking circuit of the relay 2 is opened. In this manner the selector switch SS and all of its moving members 15 return to their normal position.

What is claimed is:

1. In a telephone system, multi-group selective switches, groups and subgroups of telephone lines terminating in said switches, 20 calling devices for controlling said switches, means included in said calling devices responsive to the manner in which said calling devices are set for transmitting an impulse over said lines, means responsive to the setting of said calling devices for setting said switches in relation to a particular group of said lines, and a differentially wound relay responsive to said first means for setting said switches in relation to a 25 particular subgroup of said lines within said selected group of lines.

2. In a telephone system, a selective switch comprising sets of terminals arranged in groups and subgroups, sets of brushes arranged in operative relation with said terminals, a primary magnet for selecting a particular group of said terminals, a differentially wound relay differently responsive to means for setting said switch for 35 selecting a particular subgroup of terminals of said selective group, and a secondary magnet for selecting a particular set of terminals in said selected subgroup.

3. In a telephone system, a selective switch 45 comprising sets of terminals arranged in groups and subgroups and sets of brushes arranged in operative relation with said terminals, telephone lines connected to said sets of terminals, calling devices associated 50 with said lines at the distant end thereof, a

source of current, means for causing said current to flow in equal volume over both sides of said lines, a primary magnet responsive to the intermittent flow of said current for setting said switch in association 55 with a group of said terminals, means included in said calling devices for unbalancing the flow of current in said line, means responsive to the unbalanced flow of said current for setting said switch in association 60 with a particular subgroup of said lines in said selected group, and means for setting said switch in association with a particular set of terminals in said selected subgroup 65 of said selected group.

4. In a telephone system groups and subgroups of telephone lines, selective switches for interconnecting said lines, impulse transmitters for controlling said switches, means included in said transmitters responsive to 70 the different manner in which said transmitters are set for differently affecting said lines, means included in said switches responsive to the actuation of said impulse transmitters for selecting groups of said 75 lines and lines in said groups, and differentially wound relays included in said switches differently responsive to the different manner of setting of said impulse transmitters for selecting sub-groups of said 80 selected groups.

5. In a telephone system, telephone lines, each equipped with a sender means included in said sender responsive to the different manner in which said sender is set for 85 differently affecting said lines, divided into groups and sub-groups, an automatic switch for extending a line to any one of said lines in said sub-groups, a differential relay differently responsive to the different manner 90 of setting of said senders for selecting one of said groups, means responsive to the actuation of said senders for selecting a sub-group in said selected group, and means for selecting a line in said selected sub-group.

In witness whereof, we hereunto subscribe our names this 13th day of July, A. D. 1917.

HENRY P. CLAUSEN.
CHARLES L. GOODRUM.
